UNITED STATES PATENT OFFICE.

CHARLES B. HANNA, OF MINNEAPOLIS, MINNESOTA.

SELF-SEALING BURIAL VAULT.

Application filed January 14, 1921, Serial No. 437,296. Renewed July 21, 1923.

To all whom it may concern:

Be it known that I, CHARLES B. HANNA, a citizen of the United States, residing at St. Louis and State of Missouri, have invented certain new and useful Improvements in Self-Sealing Burial Vaults; and I do hereby declare the following to be a full, clear, and exact description of the invention, such as will enable others skilled in the art 10 to which it appertains to make and use the same.

My invention has for its object to provide a self sealing burial vault, and to this end, it consists of the novel devices and combinations of devices hereinafter described and defined in the claims.

In the accompanying drawings, which illustrate the invention, like characters indicate like parts throughout the several 20 views.

Referring to the drawings:

Fig. 1 is a perspective view of the improved burial vault;

Fig. 2 is a plan view with the cover removed by sectioning its capping flange;

Fig. 3 is a detail view principally in vertical section taken on the line 3—3 of Fig. 2, on an enlarged scale; and

Fig. 4 is a detail view with some parts 30 sectioned on the line 4—4 of Fig. 3.

The improved burial vault comprises a box 5 and a cover 6, both of which are formed from sheet steel, the joints at the corners thereof being tightly closed by 35 welding or other suitable means. The sides and end walls of the box 5 are reinforced by pressing the same outward to afford upper, lower and intermediate longitudinal ribs 7. Casket-supporting flanges 8 are formed on 40 the bottom of the box 5 by transversely pressing the same upward. Formed with the cover 6 is an endless depending flange 9 adapted to cap the box 5 and rest on a supporting ledge 10 formed on the upper edge 45 of the upper reinforcing rib 7. The cover 6 is reinforced by pressing the same upward to afford an endless rib 11.

Referring now to the self sealing feature 50 of the invention, there is secured to the under side of the cover 6 a multiplicity of depending brackets 12 having pockets 13. These brackets 12 are welded or otherwise rigidly secured to the cover 6 and arranged to slide into the box 5 in close contact with 55 the sides and ends thereof. The pockets 13 open through the outer ends of the brackets

12 and the bottoms thereof are inclined toward said outer ends. It will be noted that the outer ends of the brackets 12, below the pockets 13, are inwardly and downwardly 60 curved so that when the cover 6 is applied to the box 5 said brackets will readily slide into the box 5. Just before the cover 6 is applied to the box 5, the pockets 13 are filled with tow or waste saturated with a liquid or 65 plastic iron cement indicated as an entirety by the letter Z.

The tow or waste will hold the cement while the cover 6 is being applied to the box 5, but after the cover 6 is in position, the entire 70 mass Z will run or slide into the inclined bottoms of the pockets and against the side and end walls of the box 5 and into the recess afforded by the upper reinforcing rib 7 and harden. When the cement is hard, the cover 75 6 will be securely sealed to the box 5 and cannot be removed. The capping flange 9, when seated on the ledge 10, affords a tight joint between the box 5 and cover 6. Preferably, the entire burial vault will be 80 enameled to improve the appearance thereof and also greatly increase its life. By constructing the burial vault of sheet steel, it makes the same comparatively light and easy to handle or ship. The upper reinforcing 85 rib 7 keeps the upper portion of the box 5 in true form so that the capping flange 9 will tightly fit thereon and seat on the ledge 10.

What I claim is:

1. The combination with a box, of a cover having a pocket slideable into the box in close contact therewith, said pocket being arranged to receive a plastic cement adapted to run into contact with the box and harden 90 after the cover is applied.

2. The combination with a box having in its inner wall a recess, of a cover having a pocket slideable into the box in close contact therewith at said recess, said pocket being arranged to receive a plastic cement adapted to run into contact with the box and recess 95 and harden after the cover is applied.

3. The combination with a box having an outwardly pressed reinforcing rib, of a cover having a pocket slideable into the box in close contact therewith, said pocket being arranged to receive a plastic cement adapted to run into contact with the box and rib and harden after the cover is applied.

4. The combination with a box having an outwardly pressed reinforcing rib, of a cover

having a flange capping the box and supported on said rib, a cover having a pocket 5
slidable into the box in close contact therewith, said pocket being arranged to receive
a plastic cement adapted to run into contact with the box and rib and harden after the
cover is applied.

5. The combination with a box, of a cover
having on its under side a pocketed bracket
10 slidable into the box in close contact therewith, said pocket being arranged to receive
a plastic cement adapted to run into contact

with the box and harden after the cover is applied.

6. The combination with a box, of a cover 15
having on its underside a multiplicity of
pocketed brackets slidable into the box in
close contact with the sides and ends thereof,
said pocketed brackets being arranged to re-
ceive a plastic cement adapted to run into 20
contact with the box and harden after the
cover is applied.

In testimony whereof I affix my signature.
CHARLES B. HANNA.
